UNITED STATES PATENT OFFICE.

FRANK P. DERR, OF BALTIMORE, MARYLAND.

ELECTRIC-RAILWAY CONSTRUCTION.

SPECIFICATION forming part of Letters Patent No. 693,244, dated February 11, 1902.

Application filed September 11, 1901. Serial No. 75,093. (No model.)

To all whom it may concern:

Be it known that I, FRANK P. DERR, a citizen of the United States, residing at Baltimore, in the State of Maryland, have invented certain new and useful Improvements in Electric-Railway Construction; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and useful improvements in electric-railway construction; and it has for its objects, among others, the provision of a simple, efficient, and comparatively inexpensive electric-railway system wherein the overhead trolley poles and wires may be dispensed with and a simple and efficient means provided for conducting the current of electricity within the interior of a hollow or two-part rail, which rail serves as the rails or track upon which the wheels of the car travel.

To these ends and to such others as the invention may pertain the same consists in the peculiar construction and in the novel combination, arrangement, and adaptation of parts, all as more fully hereinafter described, shown in the accompanying drawings, and then specifically defined in the appended claim.

The invention is clearly illustrated in the accompanying drawings, which, with the letters of reference marked thereon, form a part of this specification, and in which—

Figure 1 is a side view showing a portion of a car upon the track. Fig. 2 is an enlarged longitudinal section of one of the rails, showing the arrangement of the conductor-bar therein. Fig. 3 is an enlarged transverse section, and Fig. 4 is an enlarged detail in perspective, of a portion of one of the rails.

Reference now being had to the details of the drawings by letter, A designates one of the railway-rails, which is composed of two halves or sections A' and A'', preferably made of rolled steel, each of the said sections consisting of an upright or body portion A³ and a top portion B, extending at right angles to the body portion. These bisected or two-part

rails are designed to be set into recesses formed in the cross-ties, to which they are secured, as shown in Fig. 3 of the drawings, 55 thus providing a secure seat upon the cross-ties, and the rails are secured to the ties and suitably braced by means of brace-plates D, the bases of which plates are secured to the upper face of the tie, while the upright portion of the said base-plate is bolted to the rail, as shown at a a. When the rail-sections A' and A'' are bolted in place, an intervening space E is provided between the inner edges of the flanged portions B of the rail-sections, thus providing a longitudinal slot 60 extending longitudinally of the rail, within which the trolley shaft or pole travels, as will presently appear.

F is a conductor for the electric current 70 and may be of any suitable form or material, in the present instance it being shown as triangular in cross-section. This conductor is carried upon suitable supports, as shown at H, being insulated therefrom, as shown, by the 75 insulating material G. The conductor F extends directly beneath the slot or opening E, which is provided between the sections of the rail and with them engage the trolley-wheel I, carried by the shaft of pole J, through the 80 medium of which the current is conducted to the motor located upon the car, as is the case where current is conducted from the conductors employed in connection with the ordinary forms of underground systems. In order to 85 insure perfect contact of the trolley-wheel with the conductor, the shaft of pole carrying the trolley-wheel is provided with a spring K, by the tension of which a uniform pressure of the trolley-wheel upon the conductor is at 90 all times assured.

It will be at once noted that as both of the rails upon which the car travels is designed to be constructed as above described in case it should be desired both rails may be used simultaneously for conducting electricity, and the car can thus be supplied from both sides at once. Hence by providing both trucks of the car with motors one could receive its current from one side and the other from the opposite rail, it being proposed to have the pole or shaft of the trolley-wheel travel immediately in the rear of the car-wheels upon one or both sides of the car, as preferred.

Having thus described my invention, what I claim to be new, and desire to secure by Letters Patent, is—

A conductor for electric railways, comprising in combination with the inverted-L-shaped rail-sections, the recessed ties, the base-plates seated in said recesses and on which said rails are supported, the conductor and T-shaped supports therefor, resting on said base-plates, and the angle-plates se-

cured to the upper surfaces of the ties, and to the outer faces of said rail-sections and holding the latter securely in place, substantially as shown and described.

In testimony whereof I hereunto affix my signature in presence of two witnesses.

FRANK P. DERR.
